UNITED STATES PATENT OFFICE.

ARTHUR ATWATER KENT, OF ARDMORE, PENNSYLVANIA.

RADIO APPARATUS.

Application filed July 21, 1922. Serial No. 576,423.

My invention relates to apparatus utilizable more particularly in radio telephony or telegraphy, but utilizable also for amplifying, or detecting and amplifying, electrical effects, in general, and comprising thermionic devices or vacuum tubes of the audion type, or equivalent, and means for correlating or coupling them.

In one of its aspects, my invention comprises a unit consisting of a plurality of thermionic devices mounted upon a wall or cover of a casing, with associated parts mounted upon the interior of the wall or casing, and appurtenant apparatus, as coupling means, disposed within the casing.

My invention resides also in a unit for coupling thermionic devices and comprising an impedance or inductive reactance and a condenser.

20 My invention resides also in a disposition of impedances or inductively reactive coupling devices placed adjacent each other and so disposed, wound or connected that undesired oscillations, particularly those of 25 audio frequency causing "howling", will be prevented.

My invention resides in further features of structure, combination and arrangement hereinafter described and claimed.

30 For an illustration of one of various forms my invention may take, reference is to be had to the accompanying drawings, in which:

35 Figs. 1 and 2 are side elevational and top plan views, respectively, of apparatus embodying my invention.

Fig. 3 is a plan view of the under side of the casing cover showing the coupling units therein in section.

40 Fig. 4 is a horizontal sectional view, partly in plan.

Fig. 5 is a vertical sectional view of the apparatus.

45 Fig. 6 is a diagrammatic view of a circuit arrangement.

Fig. 7 is a fragmentary diagrammatic view explanatory of the relation of the coupling devices.

50 Referring to the drawing, 1 is a base of sheet metal having formed therein the annular upstanding rib 2 within which is received and secured, as by welding or otherwise, the cup-shaped casing 3, which may be provided with the bottom 4.

55 Forming a wall or closure for the casing

3 is the cover 6 having the integral flange 7, preferably of insulating material, such as molded condensite, bakelite or the like.

Disposed upon the outside of the cover 6 are the metallic sleeves or socket members 8 and 9, secured to the cover 6 in any suitable way. In the example illustrated, each of the sleeves or socket members 8 and 9 is adapted to receive the terminal end of a thermionic device or vacuum tube, as an audion, or equivalent, and comprising, as 70 well understood in the art, a filament cathode, an anode, and a control electrode, the latter generally a grid disposed between the anode and cathode. The sleeve or base of the vacuum tube carries a pin, which is 75 adapted to engage in the bayonet slot 11 in the sleeve or socket member 8 or 9 for holding the vacuum tube in position. At the base of the vacuum tube are provided two terminals for the filament, a terminal for 80 the grid, and a terminal for the anode or plate, these terminals engaging and electrically contacting with the spring or resilient sheet metal terminals disposed on the under side of the cover 6 in association with 85 each of the socket members 8 and 9. With the socket 8 are associated the filament terminal springs or contacts 12 and 13, grid spring or contact 14, and anode spring or contact 15, the ends of these contacts being 90 disposed beneath the openings 16 in the cover 6. The contacts on the base of the audion project through the opening 16, the filament terminals engaging the contacts 12 and 13, the grid terminal engaging the contact 14, and the anode terminal engaging the contact 15. These contacts are secured to the under side of the cover 6 by any suitable means, as, for example, the screws 17 extending upwardly through the cover 6 and 100 secured by the nut members 17^a.

For the vacuum tube received in the socket 9 there are similarly provided on the under side of the cover 6 the filament springs or contacts 18 and 19, the grid spring or 105 contact 20 and the anode or plate contact or spring 21, secured to the cover 6 by any suitable means, as screws and nuts 17 and 17^a. The yielding ends of these contacts are disposed beneath the circular aperture 110

22 in the cover 6, and through the aperture extend the terminals on the end of the vacuum tube, the filament terminals engaging the contacts 18 and 19, the anode terminal engaging the contact 21, and the grid terminal engaging the contact 20.

Supported upon the under side of the cover 6 are grid leak resistance members 23 and 24 constituting high resistances connected, respectively, between the aforesaid contacts 12 and 14, and contacts 18 and 20.

Carried on the under side of the cover 6 is the filament rheostat 25 comprising a resistance wire wrapped around the flat strip member 26 of insulating material, and secured flatwise by screws 27 to the cover 6. The filament contacts 13 and 18 are connected together and to the rotatable contact 28, movable across the resistance wire 25 by the handle or knob 29 on the outside of the cover 6 having the position indicating member 29^a and attached to the contact lever 28 by the shaft 30 extending through cover 6.

25 Carried by the cover 6 are the binding posts 31 to 36 inclusive for facilitating the connections to externally employed telephone or other receiving instrument T, Fig. 6, anode or plate circuit battery B, filament battery A, and thermionic device, audion or vacuum tube V and its connections.

Within the casing 3 are disposed the impedances or inductive reactances I and I¹ for effecting couplings of the character hereinafter described. These impedances may be radio frequency impedances, generally without magnetic cores, in case amplification at radio frequency is desirable. Or, as indicated, these impedances may be audio frequency impedances, where amplification is to be effected at audio frequency; or one of them, as I, may be a radio frequency impedance, while the other, as I¹, may be an audio frequency impedance, according to circumstances or desire. As illustrated, each of the impedances I, I¹ comprises a coil 37, of fine wire of great number of turns, disposed upon an insulating sleeve 38, Figs. 4 and 5, within which is disposed the magnetizable core 39, consisting of a bundle of fine iron wires. Forming units with the impedances I and I¹ are the condensers K and K¹, which may be of any suitable type. In the example illustrated, each of the condensers is of the so-called rolled type, comprising alternating strips of insulating material and tin foil rolled into a unit. Each condenser unit is disposed upon its associated impedance or coupling unit, and is 50 suitably bound thereto, as by binding member 40.

The impedance-condenser units are suitably positioned within the casing C, as hereinafter described, and are preferably held 55 in place and shielded against access of moisture by the insulating material 41, which is poured in the fluid state and then congeals or hardens, such insulating material being wax, asphaltic material or equivalent.

One terminal of the condenser K connects by conductor 42 with the grid contact 14, while the other terminal of the condenser K is connected to the outer terminal of the impedance I, and these two terminals 70 connect by conductor 43 with the binding post 31, the other terminal of the impedance I connecting by conductor 44 with the binding post 32.

Similarly, one terminal of the condenser K¹ connects by conductor 45 with the grid contact 20, while the other terminal of the condenser K¹ connects to the outer terminal of the winding of the impedance I¹, and these last two terminals are connected by 85 conductor 46 with the anode contact 15; and the inner terminal of the winding of the impedance I¹ connects by conductor 47 with the binding post 35.

Within the apparatus the filament contacts 12 and 19 are connected to each other, and by conductor 48 are connected to the binding post 34, while one end of the rheostat winding 25 is connected by conductor 49 with binding post 33. The plate contact 95 21 is connected by conductor 50 with the binding post 36.

Referring to Fig. 6, the aforesaid connections appear, and in addition, connections with external devices. V represents an audion or thermionic vacuum tube having the filament f, grid g and plate or anode a. The filament f is supplied by current from the aforesaid battery A, which also supplies current to the filaments of the vacuum tubes placed in the sockets 8 and 9, the rheostat 25 being in series with and simultaneously varying the current in the filaments of the vacuum tubes placed in the sockets 8 and 9. The strength of the current through the 110 filament f of the tube V is independently varied by the rheostat 51.

L is the secondary of an oscillation transformer whose primary may be traversed by the received oscillations, as in an antenna circuit or path. Shunting the inductance L is the variable condenser C for tuning the secondary circuit to the frequency of the received oscillations. Connection is made from the condenser C to the grid g through 115 the condenser C¹, shunted by a high resistance 52. The anode a is connected through the tickler coil or oscillation transformer winding 53, if and when regenerative action is required, as well understood in the art. 120 The anode circuit continues to the binding post 31 and thence through the impedance I and the entire or any suitable portion of the battery B, in the example illustrated, one-half of the battery B being employed. 130

The plate circuit returns through the battery B to the binding post 34, and thence by conductor 54 to one terminal of the filament f, which filament is also connected to the other terminal of the condenser C. A condenser C² may also be employed between the filament f and the connection to the anode a.

The impedance I¹ is in the anode circuit comprising the anode terminal 15 of the vacuum tube received in the socket 8. In circuit with the impedance I¹ is the entire battery B. The grid of the vacuum tube received in the socket 8 is connected through the condenser K with one terminal of the impedance I, and the filament of the same vacuum tube is connected through a portion of the battery B to the other terminal of the impedance I. The grid of the vacuum tube received in the socket 9 is connected through the condenser K¹ with one terminal of the impedance I, and the filament of the same vacuum tube is connected through the entire battery B with the other terminal of the inductance I¹. The telephone T or similar instrument or device is connected to the binding posts 35 and 36, and thereby included in the plate or anode circuit of the vacuum tube received in the socket 9, and in series with such anode circuit is the entire battery B.

Utilizing the vacuum tube V as a detector for radio telephonic or telegraphic messages or signals, there is produced across the terminals of the impedance I a potential varying in accord with the message or signal. This potential is impressed upon the grid circuit of the vacuum tube received in the socket 8, with the result that in the plate circuit of such vacuum tube there are produced corresponding variations, effecting corresponding variations of potential difference between the terminals of the impedance I¹. These potential differences are impressed upon the grid circuit of the vacuum tube received in the socket 9, and there is accordingly produced corresponding variations of current in the plate circuit thereof, including the telephone or other instrument T.

The arrangement in the example illustrated comprises, therefore, a detector V and two stages of audio frequency amplification, the apparatus unit itself being a two-stage amplifier with coupling impedances.

The impedances I and I¹ are necessarily more or less close to each other when assembled in a unit, as in a casing 3, as illustrated. If the current in the anode circuit of the detector V is zero or of small magnitude, as when there is no or only small current through the filament f, there is no or only slight current flowing from battery B through the impedance I. In such case there will be produced by the am-

plifier tubes and their circuits local oscillations, particularly of audio frequency, causing "howling", unless the impedances I and I¹, which are wound in similar directions and in general, similarly constructed, are reversed in their positions with respect to each other, as indicated in Figs. 4 and 6; or unless the impedances have their windings in such directions relatively to each other or so connected relatively to each other that the same effect is produced as by the aforesaid reversal of position. When the anode circuit current through the impedance I is small or zero, the impedance I¹, when adjacent to the impedance I, operates as the primary of a transformer inductively affecting the impedance I, which may then be considered the secondary of a transformer which, except for the aforesaid precaution, will impress upon the grid of the first amplifier tube, received in the socket 8, electro-motive-force of such direction as to cause such change in the current in the anode circuit through the impedance I¹ as to set up audio frequency oscillations.

By reversing the positions of similarly wound and constructed impedances, as indicated in Figs. 4 and 6, and with anode circuit currents flowing through both, the relation for preventing howling when the anode circuit current in one of them, as I, is zero or of small value, is such, as regards the polarity of the cores 39, that, as indicated in Fig. 7, similar ends of the cores are of different polarities, as indicated by N. S.

The casing member 3 and the bottom 1 may be of iron or steel or other magnetizable material, and yet, by observing the precautions aforesaid, no howling or audio frequency oscillations will be produced.

It is preferred that the cores 39 of the impedances be simple straight cores, as illustrated, though it will be understood that my invention is not limited in this regard and that differently disposed or shaped or arranged cores may be employed.

With core structures as illustrated, the magnetic circuit of each impedance is open in the sense that a substantial portion thereof is in air or medium other than magnetizable material, though where the bottom 1 or the casing 3 is of magnetizable material the magnetic circuits are in part through those members, particularly as regards low frequency or zero frequency currents through the impedance windings.

By the employment of impedances as described, conducting or metallic shield structure to prevent oscillations or howling is not required.

By way of example, but without limitation of my invention thereto, each of the condensers K and K¹ may have a capacity of the order of one-tenth of a microfarad; and each

- of the impedances I , I^1 may consist of a coil having a number of turns of the order of 15,000 or 20,000 turns or convolutions, of No. 38 Brown & Sharp gauge insulated copper wire, and having an ohmic resistance of the order of 2000 or 2500 ohms, and a core of the order of three-eighths or one-half inch diameter and approximately four inches length.
- 10 By apparatus of the character above described, the amplifying unit is controllable by a single rheostat, which alters the temperatures of the filaments or cathodes in like senses and to substantially like extents, such 15 adjustments of the filament currents serving to vary the loudness of the speech or signals heard in the telephone T.
- When impedances, as I , I^1 are employed as herein described within the range of influence upon each other as regards production 20 of oscillations, as audio frequency oscillations, their effects upon each other in this respect may be reduced or eliminated by enclosing one or both of them within a closed 25 or substantially closed magnetic shell; for example, each of the impedances may be disposed within an iron tube, the tube being closed at its ends by magnetizable material, or the tube given a length considerably 30 greater than the length of the impedance structure, it being understood, however, that the extra length of tube or the end closures are not in all cases or under all circumstances essential.
- 35 It shall be understood that my invention is not limited to the employment of impedances, as I , I^1 , but that in lieu of them may be used transformers, having primary and secondary windings, utilized for coupling the anode circuit of one audion to the grid circuit of the next, such transformers being either of the radio or audio frequency types, or some of them may be of radio and the remainder of audio frequency types. And 45 when transformers are so employed, they may be so placed or disposed as are the impedances I , I^1 , and are preferably embedded in insulating material in the casing 3.
- For brevity, the term "audion" is employed in the appended claims in the generic sense to include thermionic devices comprising an anode, cathode and a control electrode as a grid or equivalent.
- 50 What I claim is:
- 55 1. An audion unit comprising a casing, a cover therefor, a socket carried by said cover upon the exterior thereof, contacts carried upon the inside of said cover and adapted to engage electrodes of an audion received in said socket, audion coupling means disposed in said casing, insulating material congealed in said casing and holding said coupling means in position therein, said contacts disposed in a free space between said insulating material and cover,
- and conductors extending from said coupling means through said insulating material into said free space for connecting said coupling means in circuit.
2. An audion unit comprising a casing, a cover therefor, a socket carried by said cover upon the exterior thereof, contacts carried upon the inside of said cover and adapted to engage electrodes of an audion received in said socket, insulating material in said casing, a grid leak disposed within said casing and carried by said cover in the space between said insulating material and said cover, and audion coupling means embedded in said insulating material and supported independently of said cover.
3. An audion unit comprising a casing, a cover therefor, a socket carried by said cover upon the exterior thereof, contacts carried upon the inside of said cover and adapted to engage electrodes of an audion received in said socket, insulating material in said casing, a filament circuit rheostat carried by said cover in the space between said insulating material and said cover, means on the exterior of said cover for actuating said rheostat, and audion coupling means embedded in said insulating material and supported independently of said cover.
4. An audion unit comprising a casing, a cover therefor, a plurality of audion sockets carried by said cover on the exterior thereof, a plurality of audion coupling means, insulating material in said casing in which said coupling means are embedded and thereby held in predetermined position with respect to each other, and contacts associated with said sockets and disposed in the space between said cover and said insulating material.
5. An audion unit comprising a casing of magnetizable material, a cover therefor, a plurality of audion sockets carried by said cover, a plurality of audion coupling means, and insulating material in said casing embedding said coupling means and holding them in predetermined position with respect to each other and to said casing.
6. An audion unit comprising a casing, a cover therefor, a plurality of audion sockets carried by said cover, insulating material in said casing, a plurality of audion coupling means embedded in said insulating material, and held thereby in position with respect to each other preventing substantial coupling between them.
7. An audion unit comprising a casing, a cover therefor, a plurality of audion sockets carried by said cover, insulating material in said casing, a plurality of audion coupling means embedded in said insulating material, said coupling means being held by said insulating material with their axes substantially parallel, and connections to

said coupling means so related to each other that the coupling between said coupling means is substantially zero.

8. An audion unit comprising a magnetizable casing, a cover therefor, a plurality of audion sockets carried by said cover, insulating material in said casing, a plurality of coupling means embedded in said casing and held in predetermined position with respect to each by said insulating material, each of said coupling means comprising a magnetizable core and a winding thereon, said cores disposed substantially parallel with an adjacent wall of said casing, and substantially parallel with each other, and connections to said coupling means so related to each other than the coupling between said coupling means is substantially zero.

9. An audion unit comprising a casing, a cover therefor, audion-holding means carried by said cover, a plurality of audion coupling means in said casing, each comprising a winding, the axes of said windings disposed substantially parallel to each other, and connection to said coupling means to effect a polarity relation between said coupling means to prevent production of local oscillations.

10. An audion unit comprising a magnetizable casing, a cover therefor, audion-holding means carried by said cover, a plurality of audion coupling means in said casing, each comprising a winding, the axes of said windings disposed substantially parallel to each other, and connections to said coupling means to effect a polarity relation between said coupling means to prevent production of local oscillations.

11. A coupling unit for cascaded audions comprising a plurality of coupling inductances having magnetizable cores, a magnetizable member adjacent which said cores are disposed in substantially parallel relation to each other and closely spaced, said inductances being disposed respectively in the anode circuits of neighboring audions, said inductances being so related to each other that their magnetic fluxes are incapable of causing local oscillations in the presence of said magnetizable member.

12. A coupling unit for cascaded audions comprising a casing having a wall of magnetizable material, a plurality of audion coupling means in said casing, each of said

coupling means comprising a winding, a portion of said wall being within the region of influence of the magnetic fields produced by said windings, each of said means coupling the output circuit of one audion with the input circuit of another, said windings disposed substantially parallel to each other in close relation, and so related to each other that the mutual magnetic coupling is of a character to prevent local oscillations.

13. An audion coupling unit, comprising an enclosing casing having external terminals thereon adapted to be connected to elements of a radio receiving circuit, a plurality of choke coils within said casing, electrically connected to said terminals, a magnetic circuit for said coils comprising an internal core structure upon which each coil is mounted in side by side relation, said circuit having portions which magnetically couple said cores in mutual flux relation, and another portion which shunts a portion of said mutual flux.

14. An audion coupling unit comprising an enclosing casing, insulating material in said casing, a plurality of audion coupling means embedded in said material and held thereby in predetermined position with respect to each other and to said casing, whereby substantial coupling between said means is prevented.

15. An audion coupling unit comprising a casing of metallic material and a cover of insulation material having a plurality of external terminals thereon, insulating material in said casing, a plurality of audion coupling means connected to said terminals and embedded in said material, and held thereby in predetermined position with respect to each other and to said casing.

16. An audion coupling unit for cascaded thermionic amplifiers comprising coils having iron cores adapted to be connected in the circuits of succeeding audions, and in fixed special relation so that there is a magnetic flux coupling said coils, said coils being relatively so connected that the mutual magnetic flux is in such direction to oppose the generation of oscillations.

In testimony whereof I have hereunto affixed my signature this 20th day of July, 1922.

ARTHUR ATWATER KENT.

CERTIFICATE OF CORRECTION.

Patent No. 1,719,014.

Granted July 2, 1929, to

ARTHUR ATWATER KENT.

It is hereby certified that error appears in the printed specification of the above numbered patent requiring correction as follows: Page 3, line 22, for "I" read "Il"; page 5, line 99, claim 16, for the word "special" read "spacial"; and that the said Letters Patent should be read with these corrections therein that the same may conform to the record of the case in the Patent Office.

Signed and sealed this 24th day of June, A. D. 1930.

(Seal)

**M. J. Moore,
Acting Commissioner of Patents.**
